SLIDE FASTENER

Simon Frey, Zurich, Switzerland, assignor to Dr. Ing. Sim. Frey Gesellschaft für Industrielle Forschungen, Reg. Trust., Vaduz, Liechtenstein

Application March 21, 1955, Serial No. 495,743

10 Claims. (Cl. 24—201)

My invention relates to a slide fastener of the type comprising a pair of strips mounted along the edges of goods to be separably joined by said fastener and a slider adapted to bring interlocking means provided on the strips in nested interlocked relationship when slid on the strips in one direction and to release and separate the strips from each other when slid on in the opposite direction.

In prior slide fasteners of this type the interlocking means provided on the strips are usually a string of links providing a hook and eye or catch and latch formation for interlocking engagement between coordinated links of cooperating stringers. Therefore, the manufacture of such slide fasteners is complicated and expensive.

It is the object of the present invention to provide a slide fastener formed by a pair of continuous strips of flexible material which are mounted along the edges of the goods to be separably joined, the strips being so profiled as to be capable of an interlocking engagement. More specifically, it is an object of the present invention to provide a slide fastener of this kind which is durable and inexpensive, may be manufactured at low costs, and lends itself easily to the provision of a watertight or even airtight joint between the edges of the goods.

Further objects of my invention will appear from a detailed description of a preferred embodiment thereof shown in the drawings and the features of novelty will be pointed out in the claims. I wish it to be clearly understood, however, that such detailed description serves the sole purpose of illustrating the invention and is not intended to restrict or limit the same.

In the drawings, in which a preferred example of the novel slide fastener is illustrated,

Fig. 1 is a longitudinal section of the slider shown on an enlarged scale, the section being taken substantially along the line 1—1 of Fig. 4;

Fig. 2 is a view of the bottom of the slider taken in the direction of the arrow 2 in Fig. 1;

Fig. 3 is a side view of the slider taken in the direction of the arrow 3 in Fig. 1;

Fig. 4 is a longitudinal section taken substantially along the line 4—4 of Fig. 1;

Fig. 5 is a plan view of the slider viewed in the direction of the arrow 5 in Fig. 1;

Fig. 6 is the cross section of the slider taken along the line 6—6 of Fig. 1, and a cross section through the strips of flexible material embraced by the slider, the scale being larger than that of Figs. 1 to 5;

Fig. 7 is a cross section taken through the joined strips of the slide fastener and the ribbons connected therewith;

Fig. 8 is a cross section through one of the strips having a longitudinal dovetail-profiled groove confined by flexible walls, the walls being shown by broken lines in the position in which they are spread apart;

Fig. 9 is a cross section through the strip provided with a longitudinal dovetail-profiled rib; and

Fig. 10 is a cross section through the slide fastener

2

and the strips passing therethrough, the section being taken substantially along the broken line 10—10 of Fig. 1.

The novel slide fastener comprises a pair of continuous strips 1 and 2 of flexible material and a slider 3. These strips are mounted along the edges of the goods which are to be separably joined by the slide fastener. Each of the strips coheres to a ribbon 4, or 5 respectively, which may consist of a textile material and serves the purpose of facilitating the attachment along the edges of the goods, for instance by sewing.

The strip 2 is provided with a longitudinal groove 7 which is widened at its bottom and narrow at its mouth 32. Preferably, this groove has a profile consisting of

15 a semi-circle constituting the bottom of the groove, two closely spaced parallel lines constituting the narrow mouth portion 32 of the groove, and transitional lines 37, 38 which form an acute angle with the mouth lines. This profile will be called "dovetail profile" hereinafter.

20 The other strip 1 is formed by a base portion of substantially rectangular cross section and of a longitudinal ribbon extending from the center of the side wall of the base portion and provided with a head portion 6 of dovetail profile. As will appear from Fig. 7, the head portion

25 6 of the ribbon is adapted to be nested in the groove 7 of the strip 2. The head portion is provided with slanting faces 35 and 36 which cooperate with the faces 37 and 38 of the groove so as to firmly interlock the flexible strips when they are in the nested relationship illustrated in Fig. 7.

30 For the purpose of forming a strong joint between the ribbon 4, or 5 respectively, and the associated strip 1, or 2 respectively, the ribbon may be provided with a bulbous portion 10 extending along its edge and this bulbous portion may be embedded in the 35 associated strip, as will appear from Fig. 7. For this purpose, the strips may be provided with longitudinal cavities 8 and 9, as shown in Figs. 8 and 9. Preferably, the ribbons 4 and 5 and their bulbous edge portions 10 are cemented to the strips 1 and 2 to form a strong 40 joint capable of resisting high stresses.

35 The slider illustrated in Figs. 1 to 6 and 10 serves the purpose of bringing the strips 1 and 2 into the nested interlocked relationship shown in Fig. 7 when the slider 3 is slid on the strips in one direction, and of releasing 45 and separating the strips from each other when slid thereon in the opposite direction.

40 The slider comprises a pair of channel members 11 and 14 which are rigidly connected with each other and held in spaced opposed symmetrical relationship by a 50 spacing member 17 which may be integral with or welded to the channel members 11 and 14.

45 Each of the channel members 11 and 14 comprises a lengthy base plate tapering towards its ends, the arms 12 and 13 or 15 and 16 of the channel members constituting opposed flanges. The base plates of the channel members are slightly curved away from each other in the central portion of the slider.

55 The channel members 11 and 14 and the spacing member 17 form a Y-shaped guiding channel for the strips 1 and 2, as the sliders of slide fasteners usually do. The two branches of this Y-shaped guiding channel are designated by 28 and 29 in Fig. 1. One pair of arms 12 and 15 of the channel members serves to guide the grooved strip 2, and the other pair of arms 13 and 16 serves to guide the other strip 1.

60 The spacing member 17 is wedge-shaped when viewed as shown in Fig. 1. On its side opposed to the arms 12 and 15 the spacing member 17 is provided with a wedge-shaped portion 18. As will appear from Fig. 4, the sides 70 of the wedge-shaped portion 18 extend parallel to the upper tapering ends of the base plates of the channel members 11 and 14 so as to constitute therewith guide-

ways of constant width. These guideways serve the purpose of accommodating and guiding the flexible arms 33 and 34 of strip 2 which confine the groove thereof. When the slider is slid upwardly with respect to Fig. 1, the wedge-shaped portion 18 of the spacing member 17 slides between the flexible arms 33 and 34 of the strip 2 and spreads the same apart into the position shown in Fig. 8 by dash-dotted lines in which their distance corresponds substantially to the thickness of the dovetail-profiled head portion 6 of the ribbon of strip 1.

Each channel member is provided with an interior rib 19, or 20 respectively, which extends from the spacing member 17 substantially parallel to the pair of arms 12 and 15. As will appear from Figs. 6 and 10, the two interior ribs 19 and 20 are arranged in spaced registering relationship. Each of the interior ribs 19 and 20 is provided with a flange 21, or 22 respectively. This flange forms a ledge which constitutes a continuation of the groove-spreading side of the wedge-shaped portion 18, as will appear from Fig. 4. Preferably, the flanges 21 and 22 converge at their lower ends, as shown in Fig. 4, that is to say at the ends remote from the spacing member 17. The distance of the ribs 19 and 20 varies. At their lower ends it amounts substantially to the thickness of the thin portion of the rib projecting from strip 1. The parallel upper portions of the flanges 21 and 22 have a distance corresponding substantially to the width of the thick portion 6 of the rib of strip 1.

It is the purpose of the flanged ribs 19 and 20 to guide the flexible walls of strip 2 into and out of the interlocking relationship with the dovetail-profiled strip 1 when the slider is slid upwardly or downwardly. On its upward motion, the slider 3 guides the two strips 1 and 2 in such a manner that the thick portion 6 of the rib of strip 1 slides through between the flanges 21 and 22 and into the groove 7 of strip 2, as will appear from Figs. 10 and 6, Fig. 10 showing the strips just prior to arrival in interlocking relationship, and Fig. 6 showing the strips just before the interlock is completed on upward motion of the slider 3.

Each of the interior ribs 19, or 20 respectively, is integral with an interior rib 23, or 24 respectively, of the associated channel member 11, or 14 respectively. The ribs 23 and 24 have a width which slightly exceeds that of the central portions of the ribs 19 and 20, as will appear from Fig. 4. The two ribs 23 and 24 register with each other. Their constant distance corresponds substantially to that of the lower ends of the ribs 19 and 20. The ribs 23 and 24 extend between and substantially parallel to the opposed face of the connecting member 17 and the pair of arms 13 and 16, as will appear from Fig. 1. Hence, the elements 19 and 23, or 20 and 24 respectively, constitute a Y-shaped rib, the diverging sections of which extend parallel to the pairs of arms 12, 15 and 13, 16. It is the purpose of diverging rib sections 23 and 24 to engage and to guide the inner sides of the strip 1, as will appear from Fig. 10.

Preferably, the slider is equipped with a bail 27 for the attachment of the customary handle which serves to manipulate the slider. The ends of the bail 27 engage recesses 25 and 26 provided at the ends of the channel member 11, as will appear from Figs. 1 and 4.

When the slider is pulled in upward direction, the wedge-shaped portion 18 of the connecting member 17 enters the neck portion 32 of the dovetail-profiled groove of strip 2 and spreads the arms 33 and 34 confining the groove apart to the position shown in Fig. 8 by broken lines. While the spread arms 33 and 34 slide upon the flanges 21 and 22 of the interior ribs 19 and 20, the head portion 6 of the rib of strip 1 is introduced into the widened groove 7 passing through between the flanges 21 and 22, the strip 1 being guided by the ribs 23 and 24 and the pair of arms 13 and 16, as will appear from Fig. 10. Thereafter the converging ends

of the flanges 21 and 22 permit the arms 33 and 34 to close-down upon and to engage behind the dovetail-profiled portion 6 of strip 1 until the two strips arrive in the relative position shown in Fig. 7 in which the two strips are firmly interlocked.

On downward motion of the slider 3 the flexible arms 33 and 34 of the strip 2 slide upon the converging ends of the flanges 21 and 22 and are spread apart by the same until the groove 7 has been widened sufficiently to permit removal of portion 6 of strip 1 which passes through between the flanges 21 and 22 entering the guiding channel 28. While the arms slide off the wedge-shaped portion 18, they are forcibly returned to the normal position by the converging base portions of the channel members 11 and 14.

The improved slide fastener is capable in interlocked condition to resist high stresses tending to pull the two strips 1 and 2 apart. The slanting faces 35 and 36 of the dovetail-profiled rib of strip 1 exert upon faces 37 and 38 of strip 2 forces which have inwardly directed components tending to press the two arms 33 and 34 firmly upon the narrow neck portion of the rib of strip 1. Hence, the two strips will be held together with an increasing force as the tensile stress increases. Moreover, the joint between the strips 1 and 2 is practically water- and airtight.

At least one of the strips, to wit strip 2, is preferably made of a rubber-like material, such as a suitable plastic, or rubber. Similarly, strip 1 may consist of a suitable plastic which may be less flexible than that of strip 2. Since the slider moves the arms 33 and 34 positively to their normal positions upon engagement or disengagement of the strips, the flexibility of the arms 33 and 34 need not be necessarily of such a degree as to effect the automatic restoration of arms 33 and 34.

The ribbons 4 and 5 may be simply molded in the strips 1 and 2. Preferably, however, they are cemented thereto or welded thereto. While I prefer to make the ribbons 4 and 5 of textile material, they may also consist of a suitable plastic. They are preferably connected with the marginal portions of the goods to be joined by sewing. The profile of the strips 1 and 2 is the same throughout their lengths. If desired, however, the strips may be provided with transverse grooves to increase their flexibility.

While the invention has been described in connection with a preferred embodiment thereof, it will be understood that it is capable of further modification, and this application is intended to cover any variations, uses, or adaptations of the invention following, in general, the principles of the invention and including such departures from the present disclosure as come within known or customary practice in the art to which the invention pertains, and as fall within the scope of the invention or the limits of the appended claims.

What I claim is:

1. A slide fastener comprising a pair of continuous strips of flexible material mounted along the edges of goods to be separably joined by said fastener, one strip being provided with a longitudinal dovetail-profiled groove confined by flexible walls and the other strip being provided with a longitudinal dovetail-profiled rib adapted to be nested in said groove, and a slider adapted to bring said strips in nested interlocked relationship when slid thereon in one direction and to release and separate the strips from each other when slid thereon in the opposite direction, said slider comprising a pair of channel members and a wedge-shaped spacing member rigidly connected at one end of said channel members and adapted to hold said channel members in spaced opposed symmetrical relationship, inwardly extending flanges on each side edge of said channel members arranged in pairs in opposed relation said channel members and said spacing member forming a Y-shaped guiding channel for said strips, said guiding channel being

laterally confined by the side flanges of said channel members, one pair of side flanges serving to guide said one strip and the other pair of side flanges serving to guide said other strip, said spacing member being provided on its side opposed to one of said pair of side flanges with a wedge-shaped portion adapted to engage said groove and to spread apart said walls a distance corresponding substantially to the thickness of said dovetail-profiled rib, said channel members being provided with interior ribs arranged in spaced registering relationship and extending from said spacing member substantially parallel to one of said pair of side flanges, said interior ribs being provided with angular flanges extending outwardly in the direction of the side flanges of said channel members and forming ledges constituting continuations of the sides of said wedge-shaped portion and adapted to guide said spread-apart walls in said dovetailed grooved strip, said last named flanges converging at their ends remote from said spacing member to thereby guide said walls into and out of the interlocking relationship with respect to and across said dovetail-profiled rib.

2. A slide fastener comprising a pair of continuous strips of flexible material mounted along the edges of goods to be separably joined by said fastener, one strip being provided with a longitudinal dovetail-profiled groove confined by flexible walls and the other strip being provided with a longitudinal dovetail-profiled rib adapted to be nested in said groove, and a slider adapted to bring said strips in nested interlocked relationship when slid thereon in one direction and to release and separate the strips from each other when slid thereon in the opposite direction, said slider comprising a pair of channel members and a spacing member rigidly connected with and adapted to hold said channel members in spaced opposed symmetrical relationship, inwardly extending flanges on each side edge of said channel members arranged in pairs and in opposed relation said channel members and said spacing member forming a Y-shaped guiding channel for said strips, said guiding channel being laterally confined by the side flanges of said channel members, one pair of side flanges serving to guide said one strip and the other pair of side flanges serving to guide said other strip, said spacing member being provided on its side opposed to said one pair of side flanges with a wedge-shaped portion adapted to engage said groove and to spread apart said walls a distance corresponding substantially to the thickness of said dovetail-profiled rib, each of said channel members being provided with interior Y-shaped ribs having diverging sections arranged in spaced registering relationship, the diverging sections of said Y-shaped ribs extending parallel to the corresponding pair of opposed flanges on each side of said channel members, one of said diverging sections adjoining said wedge-shaped member and the

- other one of said diverging sections extending between and substantially parallel to the opposed face of said wedge-shaped member and one of said other pair of side flanges, an angular flange being provided on each of 5 said Y-shaped ribs opposite to the other pair of opposed side flanges and extending in the direction of the side flanges of the respective channel members, such angular flanges forming ledges constituting continuations of one of the walls of said wedge-shaped member and 10 adapted to guide said spread-apart walls of said dovetailed groove strip, said flanges converging at their ends remote from said spacing member to thereby guide said walls of said strip into and out of interlocking relationship with respect to and across said dovetail-profiled rib 15 of said other strip, the latter being guided by said other one of said diverging sections of said Y-shaped ribs.
3. A slide fastener as claimed in claim 1 in which said angular flanges have parallel portions located adjacent to said spacing member and converging portions constituting the ends remote from said wedge shaped spacing member.
4. A slide fastener as claimed in claim 1 in which each of said strips has the same profile shape throughout its length.
- 25 5. A slide fastener as claimed in claim 1 comprising in addition a pair of spaced ribbons, each ribbon being provided with a bulbous portion along one of its edges, said bulbous portions being embedded in and cemented to said strips of flexible material.
- 30 6. A slide fastener as claimed in claim 1 comprising in addition a pair of spaced textile ribbons, each textile ribbon being provided with a bulbous portion along one of its edges, said bulbous portions being embedded in and cemented to said strips of flexible material.
- 35 7. A slide fastener as claimed in claim 1 in which said one strip consists of a rubber-like material.
8. A slide fastener as claimed in claim 1 in which at least one of said strips consists of a plastic.
9. A slide fastener as claimed in claim 1 comprising 40 in addition a pair of spaced ribbons of rubber-like material, each ribbon of rubber-like material being provided with a bulbous portion along one of its edges, said bulbous portions being embedded in and cemented to said strips of flexible material.
- 45 10. A slide fastener as claimed in claim 1 comprising in addition a pair of spaced ribbons of plastic, each ribbon of plastic being provided with a bulbous portion along one of its edges, said bulbous portions being embedded in and cemented to said strips of flexible material.
